PICKER CHECK

Thomas T. Boucher, deceased, late of Norwich,
Conn., by Rose A. Boucher, administratrix,
Norwich, Conn.

Application January 23, 1941, Serial No. 375,706

3 Claims. (Cl. 139—165)

This invention relates to looms and more particularly to picker checks for such devices.

One important object of the invention is to provide novel strap means and adjustments therefor to constitute picker checks.

A second important object of the invention is to provide novel means for adjusting the throw of such picker check straps.

A third important object of the invention is to provide novel spring means for controlling the resistance of the picker checks to the movement of the picker sticks in a forward direction.

With the above and other objects in view, as will be hereinafter apparent, the invention consists in general of certain novel details of construction and combination of parts hereinafter fully described, illustrated in the accompanying drawings and particularly pointed out in the appended claims.

In the accompanying drawings like characters of reference indicate like parts of the several views, and—

Fig. 1 is a plan view of a portion of a loom showing one form of the invention applied thereto.

Fig. 2 is a front elevation thereof.

Fig. 3 is an end elevation thereof.

Fig. 4 is a side elevational view showing a second form of the invention.

Fig. 5 is a plan view of the form shown in Fig. 4.

Fig. 6 is an end elevation of the form shown in Fig. 4.

Fig. 7 is a perspective view of the laterally slideable member.

Fig. 8 is a similar view of the L-shaped bracket.

In the form of the invention shown in Figs. 1, 2 and 3, there is provided a lay beam 10 having a slot 11 extending longitudinally thereof. The check device comprises a body or base member 12 which lies on top of the outer part of the beam 10 and is provided adjacent each end with a rearwardly opening slot 13. On top of each slot rests a washer 14 wherethrough extends a screw 15 which engages in the beam 10 and thus holds the base in spacial adjustment parallel to the slot 11. Extending downwardly from the base 12 is a flange 16 which serves to limit inward movement of the base 12. Extending upwardly from the rear part of the base adjacent one end thereof is a post 17 having a transversely arcuate front surface 18 and provided with a forwardly extending head 19. Projecting forwardly from the front edge of the base 12 is a lug 20 having a forwardly opening slot 21 and

extending from the front of this slot to the inner or rear edge of the base 12 is a rectangular groove 22. On the base is mounted a laterally slideable member having a foot 23 provided with a tongue 24 fitting in the groove 22. A bolt 25 extends through the foot 23 and the slot 21 and has on its lower end a nut 26. This bolt serves to clamp the foot 23 in adjusted position on the base 12. Extending upwardly from the foot 23 is a post 27 having its rear surface 28 arcuate in cross-section. Carried by the post 27 is a bracket 29 which extends toward the middle of the loom and has a widened end 30. On the face of the widened end 30 is mounted a split spring 31, J-shaped in plan with the curved end 32 of the J adjacent the slot 11. This spring 31 is secured to the end 30 by a bolt 33. Secured to the bracket 29 is an L-shaped guard member having a horizontal leg 34 secured to the top of the bracket 29 by a bolt 35. This guard member has a vertical leg 36 which depends down in spaced relation to the bracket 29. An endless strap 37 of leather or other flexible material having its peripheral wall vertical extends across the slot 11 to embrace the picker stick 38, the front side of the strap extends in front of the post 17, behind the post 27 and in front of the leg 36 while the rear part of the strap lies behind the picker stick 38. Thus, when the picker stick oscillates it hits alternately the end portions of the strap and tightens it, the portions alternately curved at the front part resisting sliding movement of the strap.

In the form of the invention shown in Figs. 4, 5 and 6 the picker stick is arranged to oscillate in a horizontal plane. In this form the lay is shown at 40 and is provided at its outer end with an angular extension 41 whereton is mounted an arm 42, the arm being provided with a slot 43 wherethrough a bolt 44 passes and is screwed into the extension 41. The arm 42 has a pair of spaced rearwardly extending arms 45 rounded on their upper sides. Also the arm 42 carries an upwardly extending arm 46 whereto is secured an L-shaped bracket 47, a bolt 48 extending through a slot 49 to permit vertical adjustment of this bracket. The bracket 47 carries an arm 49 rounded on its lower side and projecting downwardly between the arms 45. The picker stick 50 lies between the lay 40 and the arm 42. The picker stick 50 is surrounded by a strap 51 which is sinuously disposed on one side between the arms 45 and 49. Also the arm 42 is provided with a head 52 which fits loosely in a bumper strap 53 supported by a head 54 which extends

from a bracket 55 secured to the arm 42 by a bolt 56. This strap is held at one side against the head by a clamp 57 secured by the bolt 58. The arm 42 is also provided with a head 59 of inclined shape.

In each of these cases the picker stick is checked by the strap surrounding the same and the length of the throw is regulated by adjustment of the member 23 in the first instance and by adjustment of the member 49 in the second instance, these members acting to so flex the straps as to provide virtual shortening thereof.

What is claimed and desired to be protected by Letters Patent is:

1. In a picker check, a lay having a picker guide, a picker oscillatable along said guide, a bracket secured to said lay at one side of said guide, a strap of elongated loop form having side portions on opposite sides of the slot and end portions crossing said slot adjacent opposite ends of the movement of the picker, said strap loosely surrounding the picker, and means carried by said bracket and sinuously flexing one side of the strap, said means including an adjustable element slidably mounted on the bracket to move linearly toward and from the picker guide for controlling the extent of flexure of the flexed side of the strap, adjustable spring means carried by the bracket and engageable by the strap upon the picker approaching one end of its path of movement, and a single bolt passing through the bracket and securing said element and spring means in adjusted position.

2. In a picker check, a lay having a picker

guide slot, a picker oscillatable along said guide, a strap of elongated loop form surrounding said picker and having side portions on opposite sides of said slot, a bracket rigidly attached to said

5 lay at one side of the slot and including an arm arranged at right angles to the lay, said bracket being provided with a pair of spaced strap flexing elements, a third flexing element guidingly and adjustably supported from one side of said arm, a picker check spring guided for adjustment on the other side of said arm, and means common to the third element and check spring for securing them in adjusted position on said arm.

3. In a picker check, a lay having a picker guide slot, a picker oscillatable along said guide, a strap of elongated loop form surrounding said picker and having side portions on opposite sides of said slot, a bracket rigidly attached to said lay at one side of the slot and including an arm arranged at right angles to the lay, said bracket being provided with a pair of spaced strap flexing elements, a third flexing element guidingly and adjustably supported from one side of said arm, a picker check spring guided for adjustment on the other side of said arm, said spring being arranged for engagement by the strap upon movement of the picker in one direction, and a bumper extending across said slot for engagement by the strap at the other end of the travel of the picker.

ROSE A. BOUCHER,
Administratrix of the Estate of Thomas T.
Boucher, Deceased.
